UNITED STATES PATENT OFFICE.

ELMER O. BEARDSLEY AND WALTER F. PIPER, OF CHICAGO, ILLINOIS, ASSIGNEES TO THE BEARDSLEY & PIPER COMPANY, OF CHICAGO, ILLINOIS, A CORPORATION OF ILLINOIS.

MOLDING MACHINE.

Application filed December 1, 1924. Serial No. 753,095.

The invention relates to molding machines. In the operation of molding machines of the type which projects wads of sand at high speed into flasks with a projector-head that is movable horizontally to fill all portions of the flasks, it has been found to be desirable in some instances to raise or lower the head when the machine is used to fill flasks of widely varying heights. One object of the invention is to provide an improved molding machine in which the projector head is vertically adjustable for this purpose.

Another object of the invention is to provide a projector-head which is vertically adjustable by power-driven mechanism to facilitate its vertical adjustment.

Another object is to provide sand feeding mechanism which is adapted to be automatically adjusted to maintain a continuity of the feed of sand to the projector-head while it is in different vertical positions.

Other objects of the invention will appear from the description.

The invention consists in the several novel features hereinafter set forth and more particularly defined by claims at the conclusion hereof.

In the drawings:

Fig. 1 is a side elevation of a machine embodying the invention. Fig. 1^a is a detail section of the upper sand conveying belt. Fig. 2 is a plan. Fig. 3 is a vertical section on line 3—3 of Fig. 2 through the projector and the arm on which it is mounted. Fig. 4 is a plan view of the lifting mechanism, parts being shown in section. Fig. 5 is a transverse section on line 5—5 of Fig. 3 through the projector-head. Fig. 6 is an enlarged section on line 6—6 of Fig. 1. Fig. 7 is a vertical section of the parts shown in Fig. 6.

The invention is exemplified in a machine of the general type exhibited in Patent No. 1,309,833 granted to us July 15, 1919, in which a projector-head A is mounted on the free end of an arm B which is pivoted to the distal end of a jib C which is pivoted to a support so it can swing horizontally, the arm and jib forming a support for the projector-head which permits the latter to be swung hori-

zontally to any desired point within a prescribed range to project wads of sand into all portions of subjacent flasks. The projector-head comprises a casing a, a rotor comprising a body a' and a projector blade a² which coacts with a removable liner a³ to shear wads of sand from a stream fed into the casing by a belt b', as more fully set forth in an application filed by us February 28, 1924, serially numbered 695,705. The shaft a⁴ of the rotor extends longitudinally through the arm B, which is tubular for that purpose, to an electric motor D, which is carried at the inner end of the arm B. This motor also serves to drive the feed-belt b' through suitable gearing, as more fully exemplified in Patent No. 1,408,493 dated May 7, 1922. A hopper b² is carried by arm B to direct the sand onto the belt b'. Said arm is pivotally connected to the jib C by a stud b³ carried in antifriction bearings in a bracket c suitably fixed to the outer end of the jib C.

The jib C is formed of tubing and its inner end is fixedly secured in a socket 10 formed in a bracket 11. A square column 12 extends vertically through the bracket 11 and is provided with rollers 13 and 14 having V-shaped peripheries to fit the corners of the standard 12, so that the standard will turn with the jib. This standard is supported at its lower end on any suitable support, such as a housing 15, by means of an anti-friction bearing which will permit the standard to rotate freely with the jib C. A plate 16, fixed to the housing 15, carries a race 17 for balls 18 which carry a collar 19 which is fixed to the lower end of standard 12. A dust cap 20 is secured to standard 12 by a screw 21 and extends over the ball bearing to exclude sand therefrom. The upper end of the standard 12 is held against lateral displacement by a ball-bearing 22 held in a bracket 23 which is rigid with the support 15, being secured to a column 24 on the housing or otherwise suitably supported.

The column 12 is extended, as at 25, through and above the bracket 23, and a supporting bracket or table 26 is rigidly secured to the upper end thereof, so that it will turn with the column and the jib C. This bracket carries the motor and gearing for driving an

endless belt 27 for feeding sand into the chute b^2 on the arm B. The upper end of belt 27 passes around a pulley 28 which is mounted to rotate on a shaft 29 which is fixed in bearings 30 and 31 formed in a housing 32 which is bolted to the supporting bracket 26. An electric motor 33 is enclosed in said housing and a pinion 34, fixed to its shaft, meshes with a gear 35 which is keyed to the hub 36 which projects from one end of the pulley 28 to drive the sand-feeding belt 27. Housing 32 is extended, as at 32^a, to enclose said gearing and is provided with a removable side 32^b to provide access to the gearing. The 15 housing is also provided with a removable section 32^c to provide access to the motor. The lower or outer end of belt 27 is carried by an idler pulley 37. The shaft 38 of this pulley is carried by a pair of members 40, the upper 20 ends of which are pivoted to swing around the shaft 29 which carries the pulley 28, so that the lower end of the belt may be raised and lowered to maintain its operative relation with the chute b^2 in the different vertical 25 positions of the projector.

Each member 40 comprises a rod 41 provided with a bearing 42, fitting around shaft 29, a tube 43 fixed to the rod 41, and a rod 44 provided at one end with a bearing 45 for 30 shaft 38 and having its other end extended into the tube 43 and threaded for engagement with nuts 47, whereby the distance between shafts 38 and 29 may be varied to keep the sand belt 27 taut. The outer ends of 35 members 40 are retained in seats 48 in a forked bracket 49 which is fixedly secured to the jib C by a U-bolt 50. When the jib C and arm B are raised or lowered, the belt 27 and its supporting members 40 will swing vertically 40 around shaft 29 to cause the discharge end of the belt to maintain its delivery position with respect to the chute b^2 , which is movable horizontally and vertically with arms B. A baffle 51, supported by metallic straps 52 45 from the rods 44 of the belt carrying members, prevents overflow of the sand from the belt 27 and directs it downwardly into chute b^2 and onto the belt b' which delivers sand from said chute to the projector casing. A hopper 54 is supported by straps 55 from members 50, so that it will swing vertically with belt 27 and said members. Sand is usually fed into this hopper from an elevator, if the projector is used on a portable truck, or from an 55 overhead delivery, if the projector is of the non-portable type.

In operation, the sand will be fed continuously in regulated quantity from hopper 54 to belt 27 which will discharge it into chute b^2 and onto belt b' , which will feed the sand into the high speed projector. The latter is movable horizontally around the pivotal connection between the arm and the jib and also around the axis about which the jib 65 swings, so that the head may be easily moved

to project wads of sand into all portions of a subjacent flask. When it is desired to raise or lower the projector-head, the bracket 11, which carries the arm B, will be correspondingly raised or lowered. When this bracket 70 is moved, the jib C, arm B, with the projector-head and its driving mechanism and the sand feeding belt b' and hopper b^2 will be conjointly shifted, so that their operative relation will be maintained. The shift of jib C 75 will raise or lower the bracket 49 to swing the sand-feeding belt 27 and its supporting members 40 vertically around shaft 29, so that there will be no substantial change in relationship between the lower end of the belt 80 and chute b^2 carried by the jib C. The jib C, column 12, supporting bracket 26, with the motor 33, the gearing for driving pulley 28, belt 27 and supporting members 40 and bracket 49 will all swing together horizontally, so that the sand feed will be continued from hopper 54 to chute b^2 in the different horizontal positions of the jib. In other words, while the operator manipulates the projector-head horizontally into any of its desired positions, the sand-feeding means will remain effective to keep the projector continuously supplied with sand.

This construction exemplifies one in which the projector-head is mounted to be shifted 95 horizontally to project sand into all portions of a flask and is carried by supporting means which is vertically adjustable so the projector-head may be raised and lowered to effect proper delivery of wads of sand into flasks 100 of substantially different heights and in which the sand-feeding means is adjustable with the projector, so that sand will be supplied to the projector in all of its different vertical positions; also one in which a sand-feeding belt is mounted to swing horizontally 105 and is vertically adjustable with a jib which carries a sand projector.

Power operated mechanism is provided for raising and lowering the projector, its supporting structure and the sand-feeding mechanism. This mechanism comprises an electric motor 58, which is supported on a bracket 59, which is affixed to jib C by U-bolts 59^a; a pinion 60 fixed to the shaft of said motor; a gear 61 fixed to a shaft 62; a worm-wheel 63 fixed to shaft 62; a worm gear 64 driven by said worm-wheel; a shaft 65, to which the worm-gear is fixed; a drum 66 fixed to shaft 65 and a cable 67, which has its upper end anchored, as at 68, to the supporting bracket 26 and is adapted to be wound around and paid out from drum 66. Motor 58 is of the reversible type, so that the gearing may be operated in opposite directions to wind the cable or to unwind it from the drum 66. Gears 60 and 61 are enclosed in a housing 69, and worm 63 and gear 64 are enclosed in a housing 70. These housings are sectionally formed to provide for ready access to the gearings therein 125 130

and are suitably attached to the bracket 11 so that all of the jib raising and lowering mechanism will swing horizontally with the jib and move vertically therewith.

- 5 When it is desired to raise the projector-head, the motor 58 will be operated to rotate drum 66 through the intermediate reducing gearing, to wind up the cable 67, which will raise the bracket 11, jib C, arm B, projector 10 A and the bracket 49. Bracket 49 will swing the sand-feed belt 27, so that its lower end will remain in position to discharge sand into the hopper b^2 , which is movable horizontally and vertically with the arm B. When the projector-head is to be lowered, the motor will be operated in reverse direction to unwind the cable 67 the extent desired to bring the projector in its desired elevation.

20 The construction last described exemplifies power-operated mechanism for quickly and conveniently raising and lowering the projector-head and its supporting arm and jib.

25 The invention is not to be understood as restricted to the details set forth, since these may be modified within the scope of the appended claims, without departing from the spirit and scope of the invention.

Having thus described the invention, what we claim as new and desire to secure by Letters Patent is:

1. In a machine for making molds the combination of a sand projector, means for supporting the projector comprising a member pivoted to swing horizontally, means for adjusting said member vertically to raise and lower the projector comprising a motor, and a mechanically operated conveyor carried by and vertically adjustable with said supporting member for feeding sand to the projector.
2. In a machine for making molds, the combination of a sand projector, means for supporting the projector comprising a member movable horizontally, means for adjusting said member vertically to raise and lower the projector comprising a motor, and means for feeding sand to the projector comprising a belt having one of its ends pivotally supported and its other end vertically movable with the member.
3. In a machine for making molds, the combination of a sand projector, a plurality of members pivoted together and to swing horizontally, said projector being stationarily mounted on one of said members, means for vertically adjusting the other of said members to raise and lower the projector, and means for feeding sand to the projector.
4. In a machine for making molds, the combination of a sand projector, a supporting structure comprising a jib and an arm pivoted to the jib and on which the projector is mounted, said jib and arm being pivoted to swing horizontally and relatively to one another, means for vertically adjusting the jib to raise and lower the projector, and means

for feeding sand to the projector comprising a belt having one of its ends pivotally supported and its other end movable vertically with the jib and adapted to discharge sand to the arm.

5. In a machine for making molds, the combination of a sand projector, a supporting structure comprising a jib and an arm pivoted to the jib on which the projector is mounted, the jib and arm being pivoted to swing horizontally and relatively to one another, means for vertically adjusting the jib to raise or lower the projector, and sand feeding belts movable horizontally with the arm and jib respectively and vertically adjustable with the structure.

6. In a machine for making molds, the combination of a sand projector, a supporting structure comprising a jib and an arm pivoted to the jib on which the projector is mounted, the jib and arm being pivoted to swing horizontally and relatively to one another, means to support the structure in different vertical positions, means for feeding sand to the projector comprising belts, one of which is mounted on the arm and movable therewith, and the other of which has one of its ends pivotally supported and its other end vertically movable with the jib and adapted to discharge sand onto the belt carried by the arm.

7. In a machine for making molds, the combination of a sand projector, a supporting structure for the projector comprising a jib pivoted to swing horizontally, a column turning with the jib, means for vertically adjusting the jib on the column to raise or lower the projector, sand feeding means for the projector comprising a driven conveyor belt which has one end pivotally supported on the column to swing horizontally therewith and its other end connected to move vertically with the jib, and means carried by the column for driving the conveyor.

8. In a machine for making molds, the combination of a sand projector, a supporting structure comprising a jib and an arm pivoted to the jib and on which the projector is mounted, the jib and arm being pivoted horizontally and relatively to one another, means for vertically adjusting the jib to raise and lower the projector comprising a motor mounted on the jib, and means for feeding sand to the projector.

9. In a machine for making molds, the combination of a sand projector, a vertical column, a member slidable on the column and provided with a socket, a supporting structure for the projector comprising a jib mounted in the socket, means for vertically adjusting said structure to raise and lower the projector comprising a motor, and means for feeding sand to the projector.

10. In a machine for making molds, the combination of a sand projector, a vertical

column, a member slidably mounted on said column and provided with a socket, a structure for supporting the projector comprising a jib mounted in the socket, means for vertically adjusting said structure to raise and lower the projector comprising a motor and gearing, a housing for said gearing

mounted on the member, and means for feed-feeding sand to the projector.

Signed at Chicago, Illinois, this 22nd day ¹⁰ of October, 1924.

ELMER O. BEARDSLEY.
